UNITED STATES PATENT OFFICE.

WILMER G. BUCK, OF FREMONT, NEBRASKA, ASSIGNOR TO CONTINENTAL ENGINEERING CORPORATION, OF OMAHA, NEBRASKA, A CORPORATION OF NEBRASKA.

VALVE-ROTATOR FOR INTERNAL-COMBUSTION ENGINES.

1,359,669.

Specification of Letters Patent. Patented Nov. 23, 1920.

Application filed March 13, 1918. Serial No. 222,120.

To all whom it may concern:

Be it known that I, WILMER G. BUCK, a citizen of the United States, residing at Fremont, in the county of Dodge and State of Nebraska, have invented certain new and useful Improvements in Valve-Rotators for Internal-Combustion Engines, of which the following is a specification.

The present invention relates to an improvement in valve rotator mechanisms of the character shown and described in United States Patent No. 1,183,852 granted May 23, 1916, to me, for valves for gas engines, and United States Patent No. 1,244,287 granted to me October 23, 1917, for valves for internal combustion engines.

The object of the present invention is to provide a simple and effective means for automatically lubricating the rotating mechanism without altering in any material respect the component parts thereof or increasing to any appreciable extent the cost of production.

The invention further consists in the features of construction and combination of parts hereinafter described and claimed.

In the drawings:

Figure 1 is a vertical section of a portion of an engine showing the mechanism of the present invention in operative position;

Fig. 2, a cross section through the rotator mechanism; and

Fig. 3, a section taken on line 3—3 of Fig. 2, looking in the direction of the arrows.

In the art to which the present invention relates, it has been found necessary to keep certain moving parts of these valve rotator mechanisms in a lubricated condition, and owing to their position, which does not render them readily accessible, it is not practical to oil them by hand at intervals. The oiling thereof must take place automatically with the running of the engine. I have found that by a very simple means an automatic lubrication can be effected.

Referring now to the drawings, and particularly to Fig. 1, a portion is therein shown of an engine casing designated by the numeral 4. Within said casing is the usual crank shaft (not shown) actuated by the usual piston rods 5. This crank shaft runs in oil and in accordance with the well known splasher system of lubrication forces oil through an opening 6 from the crank chamber into a valve chamber 7, within which

extends the valve mechanism. The valves 8 each have a stem 9 which extends through a valve sleeve or guide 10. In the construction shown, this sleeve or guide is cast integral with a portion of the casing.

Extending directly below the valve guide 10 is a rotator mechanism, which consists of an exterior spirally threaded sleeve 11, having thereon a clutch surface 12, with which coöperates a clutch 13 affixed to the valve stem, the sleeve 11 and clutch 12 being loose with respect to said stem. The spiral sleeve travels within a barrel 14 having an interior spiral thread 15, with which the threads on the sleeve 11 mesh. This barrel terminates in an outwardly extending flange 16 on its upper end, and it is held in position by a lug 17 extending from the valve sleeve. A spring 18 is employed, extending between the flange 16 and a collar 19. This collar is mounted upon ball-bearings 20. As the valve is raised, the clutch 13 engages the clutch 12 after a predetermined upward movement of the valve has taken place, and after such clutching engagement the threads on the sleeve 11, acting in conjunction with the spiral threads 15, give a partial rotative movement to the valve. This mechanism and its operation are fully described in the previously mentioned patents and no further description is deemed necessary in the present case.

It was found necessary to provide some means for lubricating the spiral threads of the rotator device, but owing to the fact that said device was in certain instances enclosed in the engine casing, and therefore not readily accessible for periodical oiling by hand, the oiling means must be automatic in its nature and oil supplied as the engine is operated. The oil coming through the passage 6 into the valve chamber 7 is vaporized by the heat of said chamber and collects around the exterior of the valve guide 10. When sufficient of the vaporized oil has thus accumulated, it will run down the outside of said guide and into an oil collecting groove or recess 21 formed in the outer face of the flange 16. Leading from this groove or recess 21 are a series of passages or ducts 22, which may be of any desired number and which communicate with the interior of the barrel 14, and thus oil is supplied to the interior of said barrel and lubricates the spiral threads and

other parts of the rotator in the necessary manner. By this simple arrangement, a very important feature is added to the rotator device, and this is done without increasing the number of parts of the device or, to any appreciable extent, its cost of production. The oiling will be entirely automatic in nature and will continue to take place while the engine is operating.

10 Although the device has been described with considerable particularity, the invention is not deemed to be limited other than may be by the terms of the appended claims.

I claim:

15 1. An internal combustion engine having puppet valves, with rotators connected with the stems for rotating the same, said rotators being arranged within a chamber adapted to be filled with oil vapor, an oil collecting member arranged above the rotator, and means for catching the oil from said collector and directing it to the rotator for lubricating the same.

20 2. An apparatus of the character set forth in claim one, characterized by having the valve actuating mechanism arranged in a closed chamber, with passageways leading to the crank chamber, oil condensing members comprising downwardly projecting guide sleeves arranged in the top of said chamber, valve rotators positioned below said condensing members and having oil collecting rings for receiving the oil from said condensing members, said rings being provided with passageways for directing the oil to the rotators.

3. An internal combustion engine having a crank chamber, an auxiliary valve chamber, passageways leading from the crank chamber to the valve chamber for admitting vaporized oil to said valve chamber, combined valve guides and oil collecting devices arranged in the top of the chamber, valve stems projecting through said guides, rotators arranged below the guides for rotating the valve stems, said rotators being provided with flanges at their upper ends with grooves therein for receiving oil collected by said guides, said flanges also having passageways for directing the oil to the rotator.

4. An internal combustion engine having puppet valves, with rotators connected with the stems for rotating the same, said rotators being arranged within a chamber adapted to be filled with oil vapor, an oil condensing member arranged above the rotator, and means for directing the oil from said condensing member to the rotator for lubricating the same.

5. An internal combustion engine having puppet valves, with rotators connected with the stems for rotating the same, said rotators being arranged within a chamber adapted to be filled with oil vapor, an oil condensing member arranged above the rotator, a laterally extending flange arranged beneath the condensing member for catching the oil from said member and directing it to the rotator for lubricating the same.

WILMER G. BUCK.
